CALENDAR

Martin E. Trollen, St. Paul, Minn., assignor to
Brown & Bigelow, a corporation of Minnesota

Application April 30, 1934, Serial No. 723,213

10 Claims. (Cl. 40—112)

My invention relates to a desk calendar having means for readily setting the same to indicate the days of the year.

A feature resides in providing a calendar wherein a unitary operating mechanism is adapted to be supported to a base plate which is secured within the outer shell by the base plate and held in place so that the unit may be readily removed. This provides a structure wherein 10 the indicating mechanism of the calendar which designates the indicia for the days of the month in the numerals is easily assembled in a unit and may be contained within a decorative casing or housing.

15 Further, it is a feature to provide a desk calendar wherein the outer casing may be molded into the desired fanciful decorative shape to give the same an attractive appearance. In a form of casing of this character it is desirable to provide 20 an easily removable operating unit so that in assembling or replacing the operating mechanism it is unnecessary to take the casing apart. Thus I have provided a casing molded in a single piece to provide the housing for the unitary mechanism 25 of the indicia of the calendar, together with the operating levers and finger plungers which permit the calendar to be quickly adjusted and which are designed with the unit so that they may be slipped into the molded casing from the 30 bottom.

It is also a feature to provide a unitary operating mechanism for indicating the indicia by numerals of the days of the month in the form of a pair of cylinders mounted freely rotatable 35 upon a single shaft. Each of these cylinders is provided with indicia on the circumferential face thereof, one of the cylinders having the indicia from "1" to "0", while the adjacent cylinder is provided with three series of indicia from "1" to 40 "3", and with blank spaces between each set so as to permit the cylinders to be readily set in position to indicate the particular day.

45 Each cylinder is provided with a toothed escapement wheel which is adapted to be engaged by a spring urged bell-crank cam lever which cooperates with the toothed wheel to hold the drum in set position and to change the same from one position to another by a simple operation. All 50 of these features are contained in the unitary readily removable mechanism held within the one piece molded casing.

55 Features of primary importance other than those herein set forth will be more fully disclosed throughout the specification and claims.

In the drawings forming part of this specification:

Figure 1 is a perspective view of my calendar.

Figure 2 is a plan section on the line 2—2 of Figure 1.

Figure 3 is a section on the line 3—3 of Figure 2.

Figure 4 is a section on the line 4—4 of Figure 2.

Figure 5 is a perspective of the tray for holding the indicia sheets which indicate the particular month.

Figure 6 is a section on the line 6—6 of Figure 2.

Figure 7 is a similar section, showing the parts 15 in a different position.

Figure 8 is a perspective detail of the cylinder indicia operating mechanism removed from the molded casing.

My calendar A is of an attractive design having a molded casing or housing B which may be made of any material which is molded, such as bakelite, or other similar material. The casing B is molded in a single piece having a hollow inner chamber 10 with inner rib portions 11 extending from the bottom to the top of the chamber 10 on either side thereof. A base portion 12 is formed on the housing B which projects as indicated to provide a base for the rectangular body portion of the housing B which projects 20 upward from the base. The top of the housing B is arched at 13 which forms a central panel across the top and from which extends down each side a slightly projecting panel portion 14. On either side of the central panel portion over the 25 top and down the sides a marginal corner portion 15 is provided to form the front sections of the housing B.

In the front section window openings 16 and 17 are provided so that the numeral indicia of the 30 calendar which indicates the particular day of the month may appear. Above the windows 16 and 17 the month window opening 18 is formed through which the indicia 19 formed on individual sheets 20 is displayed to show the particular 35 month of the year.

The sheets 20 are held within the recess 21 of the tray 22 which is slidably supported in the slot 23 formed in the front panel 15 of the housing B. The tray 22 is formed with a decorative head 40 24 with a longitudinal ridge 25 projecting along the top of the same to add to the decorative nature of the same.

When it is desired to change the month indicia 45 19, the tray 22 is engaged by the head 24 and 50 55

lifted out of the slot 23 and the indicia sheets 29 are set in position to indicate the indicia 19 facing toward the front, such as "March", "April", etc., for each month of the year.

5 The unitary indicia operating mechanism C is assembled on the base plate 26 which is provided with screw slots 27 in the side flanges 28 formed angularly disposed from the sides of the base plate 26. The unit C is held within the casing B by the screws 29 as indicated in Figures 3 and 4. This unitary mechanism C includes a pair of cylinders 30 and 31 which are freely mounted upon the common shaft 32. The shaft 32 is supported upon its ends by the standards 33 which are formed with and project upwardly from the base plate 26. Each of the cylinders 30 and 31 are provided with toothed escapement wheels 34 which are secured to the cylinders 30 and 31 and adapted to rotate with the same or 10 cause the cylinders to be rotated when the toothed wheels 34 are rotated.

15 A spring urged bell crank cam toothed wheel operating lever 35 is pivotally secured at 36 to the standard 33 and is urged in one direction by 20 the coil spring 37 as indicated in Figures 6 and 8. The lever 35 is forked on one end to provide the cam operating dogs 38 and 39. The free ends of these cam operating dogs are formed to fit between the teeth on the toothed wheels 34 as indicated in the drawings. Normally the cam dog 38 urged by the coil spring 37 engages between two of the teeth of either of the wheels 34 to hold the cylinder in a set position. This holds the cylinder to which the wheel is attached in a set 25 position.

30 The lever 35 is formed with an operating end having an upper flange 40 and a lower flange 41. The upper flange 40 is formed with a hole 42 extending through the same so as to freely receive the lower end of the operating rod 43. The end 44 of the rod 43 rests upon the flange 41. Secured to the upper end of the rod 43 I provide a flat operating button 45 which has a head portion with a longitudinal projecting ridge similar to the head of the tray 22 to provide a decorative design to the operating button. For convenience I have numbered the button 45 which operates the lever 35 for operating the cylinder 31, and the button 45' operates the cylinder 30. 35 The cylinder 31 is provided with numeral indicia 46 from "1" to "0", while the cylinder 30 is provided with three sets of indicia 47, from "1" to "3". Between the sets of indicia 47 on the cylinder 30 blank spaces 48 are provided so that 40 only the indicia on the cylinder 31 will be indicated through the window 17, when the indicia 46 is operating to indicate the first nine days of the month. Thereafter the indicia 47 comes into 45 display through the window 16 by operating the button 45'.

50 In manufacture the casing B is molded in a single integral part open at the bottom to receive the unit mechanism C. The mechanism C is fully assembled and the rods 43 are set in 55 place in the openings 42 and then the unit C is slipped up into the opening in the bottom of the casing B with the buttons 45 and 45' projecting through the slots 50. The coil springs 37 hold the buttons 45 and 45' with the shoulder portions 51 engaging against the shoulder 52 on the inside of the casing B. Screws 29 hold the unitary 55 assembled mechanism C in operative position in the casing B as illustrated.

56 In operation the desk calender A rests upon the base 12 and the indicia 19 is set to indicate

the month of the year, while the buttons 45 and 45' are operated to rotate the cylinders 30 and 31 to indicate the indicia through the windows 16 and 17. The operation of the rotation of either of the cylinders 30 or 31 is carried out by pressing upon the button 45 which moves the lever 35 from the position illustrated in Figure 6 to the position illustrated in Figure 7. It will be noted that as the lever is operated in this manner the cam dog end 38 will be released from the teeth of the wheel 34 and as the end 38 releases from the teeth 34 the end 39 simultaneously begins to engage the teeth of the wheel 34 on the opposite side with a cam motion in the oscillation of the lever 35 by quickly pressing the button 45, so that the ends 38 and 39 act as propelling cams on the teeth of the wheel 34, thereby rotating the cylinder 30 or 31. Thus the cylinders 30 and 31 are rotated a step at a time by the reciprocating movement of the button 45 or 45'. 10 This sets the calender A quickly and easily to indicate the proper indicia 46 and 47 through the windows 16 and 17 to indicate the particular day of the month. When the button 45 is released, the dog 38 urged by the spring 37 holds the cylinder locked against rotation. This simple operating mechanism permits the calender A to be quickly set at any time.

15 The molded housing B, together with the unitary operating mechanism C are important features of my calendar which provide a simple inexpensive structure where the parts may be readily replaced or interchanged when it is desired. The housing B of the calendar A is of an attractive design as illustrated. It is apparent, however, that any suitable design may be employed where the housing or casing B is hollow and capable of replaceably supporting the unitary operating mechanism such as C.

20 In accordance with the patent statutes I have described the principles of my calendar and while the design and structure is of a nature such as I have illustrated, I desire to have it understood that this is only suggestive and that the same may be carried out by other means and 25 applied to uses other than those above set forth within the scope of the following claims:

I claim:

1. A calendar including, a molded single piece casing having a base, an opening formed in the bottom of said casing, a hollow chamber within said casing, and a unitary indicia operating mechanism supported by a base plate within said casing spaced upwardly from said base with the indicia appearing through the face of said casing.

2. A calendar comprising, a molded hollow casing formed in a single piece, indicia window openings formed in the front face of said casing through which the numerals indicating the days of the month may be seen, a window for monthly indicia adjacent the day indicia windows, a releaseable tray for supporting said monthly indicia sheets, a pair of slots formed in the back of the top of said casing, an opening in the bottom of said casing, and unitary indicia mechanism for indicating the days of the month with operating buttons projecting through said slots in the top of said casing, said unitary mechanism having a bottom supporting plate which is adapted to hold said mechanism within said hollow body of said casing.

3. A calendar comprising, an outer molded casing, window openings for indicia to indicate the days of the month, window openings for indicating the month of the year indicia, a tray for re-

- movably supporting a series of monthly sheets, a slot in the top of said casing for receiving said tray, a hollow inner chamber formed in said casing, indicia cylinders and supporting base plate
- 5 means having a unitary character adapted to be supported in said hollow chamber, escapement wheels carried by said cylinders, and spring urged oscillatable cam dogs adapted to rotate said cylinders to set the indicia to indicate the day of
- 10 the year through said windows formed in said casing.
4. A desk calendar having a unitary nature, one unit portion forming the outer casing and molded with a hollow inner chamber, the other portion forming an indicia mechanism including a pair of rotatable cylinders having numeral indicia on the faces thereof and unitarily supported on a base which secures the unit mechanism within the unit casing, finger engagement buttons extending out of said casing for operating said cylinders, toothed wheels secured to said cylinders, and oscillatable spring urged unitary cam dogs operated by said buttons to rotate said indicia cylinders.
- 25 5. A calendar indicia indicating mechanism including, a pair of rotatable cylinders, toothed wheels secured to each of said cylinders, a common shaft for supporting said cylinders freely rotatable thereon, a base for supporting said shaft, a double headed escapement bell crank cam dog for each of said toothed wheels, spring means for holding one of said heads of said cam crank into engagement between the teeth of said toothed wheel to hold the indicia cylinder stationary, said cam crank being adapted to propell the cylinder when tripped and oscillated into released and engaging position, so that first one and then the other of said cam dog heads engage the toothed wheel.
- 30 6. Calendar indicia operating unit mechanism including, a supporting base, standards extending from said base, a shaft supported by said standards, a pair of cylinders mounted freely rotatable upon said shaft, a toothed wheel carried by each of said cylinders, and a spring urged double headed cam driving bell crank including a pair of opposed cams on one end, and an operating arm at the other end adapted to drive

the toothed wheel by an oscillating motion and acting to lock the same in a set position when at rest and means engaging said arm and extending from said casing.

7. An operating mechanism for a calendar having a unitary nature including, a supporting base, a rotatable cylinder, a shaft for freely mounting said cylinder on said base, a toothed locking and rotating wheel carried by said cylinder, and a double headed cam bell crank lever spring urged, adapted to drive said toothed wheel and cylinder by the oscillation of said lever.

8. A desk calendar including, a molded hollow casing having a supporting base, a windowed front face to indicate indicia showing the month of the year and the particular day by numeral indicia, supporting means slidably held in said casing for holding said month indicia, a unitary daily numeral indicia removably supported within said casing comprising a pair of rotatable wheels having the indicia on the peripheral face thereof, and means for operating said wheel a step at a time to set the calendar to indicate the particular numeral indicia for the particular day to be indicated.

25 9. A desk calendar including, a unitary housing, a unitary rotatable indicia cylinder means within said housing, button means for operating said indicia cylinder means to set the indicia to indicate by numerals the particular day of the month, indicia showing the month of the year, and means slidably held in said casing for holding said month indicia.

30 10. A desk calendar including, a unitary outer casing, windows in the face of said casing to indicate the indicia for the month and the numerals for the day of the year, a removable unitary indicia mechanism for the numerals for the days including a supporting base plate, a hollow chamber within said casing adapted to support said unitary indicia mechanism, and finger engaging button means slidably extending out of said casing adapted to operate said indicia mechanism by pressing thereupon to indicate the numeral for the day of the year through said window openings in said casing.

MARTIN E. TROLLEN.
